UNITED STATES PATENT OFFICE

115,373

DESIGN FOR A TEXTILE FABRIC

Curt E. Forstmann, Montclair, N. J.

Application April 7, 1939, Serial No. 84,120

Term of patent 14 years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

The figure is a plan view of a piece of fabric embodying the design.

The design embodies a series of spaced diagonal

stripes each comprising three closely arranged parallel cords, the cords having a twisted appearance resulting from the floats which constitute the cords lying side by side, parallel and at a slight inclination to the axis of the cords, the background between the stripes showing a plain sunken surface.

I claim:

The ornamental design for a textile fabric, as described and as shown.

CURT E. FORSTMANN.
